(57) **CLAIM**

The ornamental design for a heating system for desoldering iron, as shown and described.

DESCRIPTION

FIG. 1 is a perspective view of the heating system for desoldering iron with the rest of the desoldering iron in broken lines;

FIG. 2 is a top, front, left side perspective view of the heating system;

FIG. 3 is a top, rear, left side view thereof;

FIG. 4 is a top view thereof;

FIG. 5 is a bottom view thereof;

FIG. 6 is a right side view thereof;

FIG. 7 is a left side view thereof;

FIG. 8 is a front view thereof; and,

FIG. 9 is a rear view thereof.

The broken lines show portions of the soldering iron which form no part of the claimed design.

1 Claim, 5 Drawing Sheets
